UNITED STATES PATENT OFFICE.

FRANK E. HOUSH, OF BRATTLEBOROUGH, VERMONT.

TROUSERS-STRETCHER.

SPECIFICATION forming part of Letters Patent No. 472,655, dated April 12, 1892.

Application filed August 18, 1891. Serial No. 403,068. (No model.)

To all whom it may concern:

Be it known that I, FRANK E. HOUSH, a citizen of the United States, residing at Brattleborough, in the county of Windham and State of Vermont, have invented certain new and useful Improvements in Garment-Stretchers; and I do hereby declare the following to be a full, clear, and exact description of the invention, such as will enable others skilled in the art to which it appertains to make and use the same.

This invention relates to improvements in garment-stretchers, which will be hereinafter more particularly described and pointed out.

In the accompanying drawings, forming part of this specification, Figure 1 is a plan view of the apparatus. Fig. 2 is a longitudinal section of the same with the lever elevated. Fig. 3 is another longitudinal section with the lever extended to stretch the garment.

A A' are two clamps constructed in the usual manner, having the adjustable metal straps α and thumb-screws α' . On the inside 25 of the upper bar of clamp A is a metal flanged plate B, having jaws b, in which is pivoted a lever C, to the under side of which is a lever C', pivoted at c. The lower end of lever C' is pivoted to a sliding sleeve D at d. In sleeve 30 D is a set-screw E.

F is a rod, which has a handle f, and the rod F extends through holes in the upper bar of both clamps A A'. On that part of the rod F between the sleeve E and clamp A' is 35 a loose coiled spring G.

H is the garment placed between the clamps.

To operate the apparatus, the garment H is put between the upper and lower bars of the clamps A A' and the screws α' are tightened so as to clamp the garment and hold it in position. The levers C C', sleeve D, and spring will then be as represented in Fig. 2. Bring down the lever C to the position in Fig. 3 and the two clamps A A' will be correspondingly separated, and consequently the material H 45 will be stretched. The sleeve D being adjustable with a set-screw to secure it at any point on the rod F gives a great advantage in stretching the garments.

I claim—

1. In a garment-stretcher, the combination of the clamps A A', the rod F, extending through and between the clamps and having thereon the sleeve D, regulated by the clamp-screw E, and the toggle-levers C C', substantially as and for the purpose described. 50

2. In a garment-stretcher, the combination of the clamps A A', the rod F, extending through and between the clamps and having thereon the sleeve D, regulated by the clamp-screw E, the spring G, and the toggle-levers C C', substantially as described. 60

In testimony whereof I affix my signature in presence of two witnesses.

FRANK E. HOUSH.
